(57) **CLAIM**

The ornamental design for an endoscope, as shown and described.

DESCRIPTION

FIG. 1 is a bottom, left side perspective view of the endoscope;

FIG. 2 is a top down view thereof;

FIG. 3 is a bottom up view thereof;

FIG. 4 is a right side view thereof;

FIG. 5 is a left side view thereof;

FIG. 6 is a front view thereof;

FIG. 7 is a back view thereof;

FIG. 8 is a bottom, left side perspective view of a second embodiment of the endoscope;

FIG. 9 is a top down view thereof;

FIG. 10 is a bottom up view thereof;

FIG. 11 is a right side view thereof;

FIG. 12 is a left side view thereof;

FIG. 13 is a front view thereof; and,

FIG. 14 is a back view thereof.

The broken lines shown in FIGS. 1-14 represent unclaimed portions of the endoscope and form no part of the claimed design.

1 Claim, 12 Drawing Sheets
